(57) **CLAIM**

The ornamental design for a personal care implement, as shown and described.

DESCRIPTION

FIG. 1 is a front perspective view of a personal care implement according to our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines shown in FIGS. 1-8 illustrate portions of the personal care implement that form no part of the claimed design. The dot-dash broken lines shown in FIGS. 1-8 illustrate the bounds of the claim and form no part of the claimed design.

1 Claim, 5 Drawing Sheets(56)
